Primary Examiner — Barbara Fox*Assistant Examiner* — Mehri F Bajoul(74) *Attorney, Agent, or Firm* — Zollinger & Burleson Ltd.(57) **CLAIM**

The ornamental design for a vapor distributor, as shown and described.

DESCRIPTION

FIG. 1 is a perspective view of a vapor distributor showing my new design.

FIG. 2 is a front elevation view thereof.

FIG. 3 is a top plan view thereof.

FIG. 4 is a rear elevation view thereof.

FIG. 5 is a right side elevation view thereof.

FIG. 6 is a left side elevation view thereof; and,

FIG. 7 is a bottom view thereof.

The broken lines shown in the figures depict portions of the vapor distributor that form no part of the claimed design.

1 Claim, 4 Drawing Sheets(56)
